UNITED STATES PATENT OFFICE.

AUGUSTUS M. SOSA, OF CINCINNATI, OHIO, ASSIGNOR TO THE AMERICAN TOOL WORKS COMPANY, OF CINCINNATI, OHIO.

INDEXING DEVICE FOR CRANK-LATHES.

1,081,993.

Specification of Letters Patent.

Patented Dec. 23, 1913.

Application filed July 12, 1913. Serial No. 778,745.

To all whom it may concern:

Be it known that I, AUGUSTUS M. SOSA, a citizen of the United States, residing at Cincinnati, Hamilton county, Ohio, have invented certain new and useful Improvements in Indexing Devices for Crank-Lathes, of which the following is a specification.

This invention pertains to improvements in the indexing devices for crank lathes of known type and will be readily understood from the following description taken in connection with the accompanying drawings in which:—

Figure 1 is a front elevation of a known type of crank-turning attachments for lathes, the attachment being fitted with my improved indexing devices: Fig. 2 a rear elevation of the tail-end bearing and rotor, the rotor appearing in vertical section, transverse to the axis of the lathe, in the plane of line *a* of Figs. 1, 3 and 5: Fig. 3 a front elevation of a portion of the tail-end rotor, a portion of the tail-end bearing appearing in the plane of line *b* of Fig. 2: Fig. 4 a rear elevation of a portion of the tail-end bearing and rotor, parts appearing in vertical section, transverse to the axis of the lathe, in the plane of line *a* of Figs. 1, 3 and 5: Fig. 5 a vertical section of a portion of the tail-end bearing in the plane of line *c* of Figs. 2 and 4: Figs. 6 and 7, diagrams illustrating the first and second setting of the indexing device when the attachment is to work upon a double crank with crank-pins set at an angle of 180° relative to each other: Figs. 8, 9 and 10 diagrams illustrating the first, second and third settings of the indexing device when the attachment is to work upon a triple crank whose crank-pins are at an angle of 120° to each other: Figs. 11, 12 and 13 diagrams illustrating the first, second, and third setting of the indexing device when the attachment is to work upon a triple crank having crank-pins at 90° to each other: and Fig. 14 a diagram illustrating the second setting of the device when the attachment is to work upon a double crank with its crank-pins at an angle of 180° from each other, this diagram illustrating the tool-rest as forming a part of the gaging system.

In the drawings, and giving attention for the present to Fig. 1 only:—1, indicates a large head-bearing adapted to be clamped

to the bed of an ordinary engine-lathe at 55 some little distance from the face-plate of the lathe: 2, a hollow rotor journaled therein: 3, a hollow sleeve projecting from rotor 2 and provided with a flange adapted to be bolted to the face-plate of the lathe, it being understood that the axis of bearing 3 is to coincide with the axis of the lathe: 4, a tail-end bearing to be secured to the lathe at such distance from head-end bearing 1 as is called for by the longitudinal dimension 60 of the crank-shaft to be dealt with: 5, a hollow tail-end rotor journaled in tail-end bearing 4: 6, eccentrically disposed clamp-boxes projecting from the inner faces of the two rotors, the degree of eccentricity of 65 these clamp-boxes, relative to the axis of the rotors, corresponding with the throw of the crank to be dealt with, and the bore of the clamp-boxes corresponding with the diameter of the body of the crank-shaft: 7, 70 driving bars mounted for endwise adjustment in the rotors and projecting inwardly from them: 8, clamp-jaws on the inner ends of the driving-bars and adapted to grip the proper cheeks of the crank-shaft to be dealt 75 with: 9, the body portions of the crank-shaft, one portion endwise beyond the crank work being gripped in the clamp-boxes of the head-end rotor while the other body-portion is clamped in the clamp-boxes of 80 the tail-end rotor: 10, one of the crank-pins of the crank-shaft: 11, another crank-pin of the crank-shaft, Fig. 1, illustrating a crank-shaft with two crank-pins disposed at an angle of 180° to each other: 12, one 85 of the end cheeks of the crank: 13, the other end cheek of the crank: 14, the middle cheek of the crank: and 14^a, typical means for clamping the two bearings to the lathe-bed.

All of the parts thus far referred to are of 90 known construction and mode of operation, which mode of operation may be briefly described in connection with Fig. 1. It is to be understood that in crank-turning attachments of the class under consideration, the 95 clamp-boxes will be adjustable to vary the radial distance from the axis of the rotors, which is the axis of the lathe, to suit the throw of the cranks, and the crank-boxes will be provided with selective bushings to 100 provide for various diameters of the bodies of the crank-shafts. The crank-shaft having had the left hand portion of its body

placed in the clamp-boxes of the head-end rotor, and the tail-end bearing having been so adjusted toward the head-end bearing as to bring the tail-end clamp-boxes close to cheek 13, the crankshaft is so turned in the clamp-boxes as to properly center crank-pin 10, after which the clamp-boxes are tightened. The left hand driving-bar 7 is now to be so adjusted to the right that jaws 8 of 10 that driving-bar will grip cheek 12, the set-screws in these jaws serving as means, not only for gripping cheek 12, but serving also in effecting its adjustment to bring crank-pin 10 into the line of collimation represented by the axis of the two rotors. The clamp-boxes being now tightened, crank-pin 10 may be turned to correct size, predetermined allowance being left for grinding, if grinding is to be done. Crank-pin 10 having been turned, the left hand driving-bar is to be retreated and the clamp-boxes loosened, and the crank-shaft is to be turned in the clamp-boxes, to bring crank 11 into the line of collimation, after which the right-hand clamp-bar is to be shifted to the left to bring its jaws into engagement with cheek 13. The parts having been adjusted and tightened, the turning of crank-pin 11 is now to be proceeded with and completed.

30 Thus far consideration has been given only to a double crank. My improved indexing devices provide for the accurate re-setting of the crank-shaft, after the turning of the first pin, and after the turning of 35 other pins if the crankshaft should be provided with more than two crank-pins.

Proceeding with the drawings:—15, indicates a radial index hole in the periphery of each of the two rotors: 16, a second hole 40 45° in angular advance of the first hole: 17, a third hole 60° in angular advance of the first hole: 18, a fourth hole 90° in angular advance of the first hole: 19, radially sliding index pins carried by the bearings and 45 adapted to have their inner ends coöperate with the index holes in the rotors: 20, a spring at the outer end of each index-pin tending to urge the index-pin toward the rotor: 21, a pinion mounted in each of the 50 bearings, at right angles to the axes of the index pins, the teeth of these pinions engaging teeth formed on the index-pins: 22, a crank on each pinion: and 23, the pair of detent holes in each bearing to coöperate with 55 a spring detent pin on each crank.

Looking at Figs. 2 and 4 it will be observed that the bearing 4 is split or provided with a cap, the joint of separation between the cap and the base of the bearing being 60 on a horizontal line. The indexing pin is mounted in the base, in order to avoid the joint between the base and the cap, and index hole 15 is to be in such position that when engaged by the indexing pin the axis 65 of the clamp-boxes will be vertically above

the axis of the rotor. In practice I place the axis of the indexing pin 5° below the horizontal plane of the axis of the rotor.

In placing the crank-shaft in the attachment it will be found of superior convenience to have the clamp-boxes disposed vertically over the axis of the rotors. The index holes in the two rotors are to be accurately disposed in the course of manufacture of the attachment, and consequently 70 when both index pins are in index holes 15 the clamp-boxes of the two rotors will be in accurate alinement with each other and the rotors will be prevented from turning. The index pins are kept in the holes 15 by 75 the action of springs 20, and the outer detent holes 23 need not be holes in fact but may be mere stop-pins against which the detent-pins of the cranks may strike to limit the inward movement of the index pins, 80 though such limitation is not important. The inner ones of the holes 23 should be holes in fact to coöperate with the detent-pins of the cranks to hold the index-pins out of engagement with the rotors. When the 85 indexing cranks are moved to the inward position the index-pins are withdrawn from the rotors and are entirely out of action, permitting the rotors to turn in the ordinary 90 working of the attachment. By releasing 95 the detent pins of the cranks, after the rotors have been turned a short distance, the index-pins are permitted to snap into the next index holes in the rotors or, by properly dealing with the cranks, into such holes as 100 are appropriate to the desired adjustment of the cranks. The first crank-pin, pin 10 of Fig. 1, having been completely turned, it is in order to lock the rotors by means of their index pins and then to retract the driving 105 bars and loosen the clamp-boxes and turn the crank-shaft into such position as to bring crank 11 into the line of collimation, after which the jaws of the right hand driver-bar are put into action on cheek 13 110 and the turning of crank-pin 11 proceeded with.

I will now proceed to describe how the indexing devices provide for the accurate re-setting of the crank-shaft when the second pin is to be turned, so as to get the axis of the second pin directly opposite the axis of the first pin in a crank-shaft having its crank-pins at an angle of 180° to each other and also how cranks having more than two 115 crank-pins may be accurately re-set.

In the following description, which will be made in connection with the diagrams of Figs. 6 to 14 inclusive, it is to be understood that the order of procedure may be 120 varied to considerable extent without negating the results aimed at. Turning to Fig. 6 it is to be understood that rotor 5 is a duplicate of rotor 2, and that the index holes in the diagram are mere notches. 125 130

Assume that the double-crank of Fig. 1 has had its first crank-pin 10 completely turned, this crank-pin at the time occupying the position indicated for it in Fig. 6.

5 In Fig. 14:—30, illustrates the usual tool-rest supported by the lathe carriage: 31, the tool-holder supported thereby in adjustable position and carrying the tool at its inner end: 32, a wing projecting inwardly 10 from the tool-rest and adapted to enter in between the cheeks of the crank to give support to the tool-holder when the tool-holder is adjusted inwardly to working position with the tool projecting inwardly beyond 15 the wing: 33, the upper surface of the wing: and 34, a gage-block adapted to be placed temporarily upon the inner portion of wing 32, when the tool-holder is withdrawn and the tool-rest moved inwardly so as to bring 20 the inner portion of the wing under one of the crank-pins when the crank-shaft is turned in the clamp-boxes.

Going again to Fig. 6, in which 10 indicates the first crank-pin, which pin has been 25 completely turned, the clamp-boxes are to be loosened and the crank-shaft given about a half turn in the clamp-boxes, thus putting the completely turned pin 10 into the general position of rough pin 11. The tool-holder of Fig. 14 is now to be loosened and withdrawn and the tool-rest is to be moved inwardly so as to come in the path of a crank-pin as the rotors are turned. Gage-block 34 is now to be placed on wing 32 and 30 the rotors are to be turned till the index-pins engage index-holes 18, thus bringing the rotors into the position indicated in Fig. 7. The crank-shaft is now to be turned until finished crank-pin 10 rests upon gage-block 34, as indicated in Fig. 7, whereupon the 35 clamp-boxes are to be tightened and the tail end driving-bar adjusted to engage cheek 13 of Fig. 1. Crank-pin 11 has now obviously been accurately brought to the line of collimation. It is to be understood that the 40 height of the upper surface of gage-block 34 is such as to limit the turning of the crank-shaft in the clamp-boxes to an angle of 180°. If crank-pin 10 has been 45 completed by the turning then the height to the upper surface of gage-block 34 will have been arranged with reference to the diameter of the accurately sized crank-pin 10, while if that crank-pin has a predetermined 50 excess of diameter to provide for grinding then the height to the upper surface of the gage-block will be correspondingly less. The gage-block 34 is illustrated as a comparatively thin block resting on the upper 55 surface of wing 32, this being a very convenient arrangement where the wing is present and employed in the gaging operation, but it is to be understood that the gaging is, after all, done from the bed of the lathe 60 which gives support to the tool-rest.

The gage-block may now be withdrawn and the tool-holder advanced and the indexing pins retracted and locked out of position, whereupon the turning of the second crank-pin 11 may be proceeded with and completed, the system being obviously such that the two pins will be at an angle of 180° to each other. 70

In the description thus given of the resetting of a double crank, such as is illustrated in Fig. 1, very little study will lead 75 to the apprehension that only index hole 18 is essential for coöperation with the indexing-pin, though the presence of index-hole 15 is useful in bringing the clamp-boxes in 80 their upper position to facilitate the tightening of the clamping bolts.

The diagrams of Figs. 8, 9 and 10 indicate the mode of procedure with a three-throw crank in which the crank-pins are at an 85 angle of 120° to each other. In these diagrams, 24, 25 and 26 indicate the three crank-pins. In Fig. 8, 24 indicates the first crank-pin to be turned. Assuming this crank-pin to have been completely turned, 90 the rotors are turned so that the index-pins engage index-holes 17 and hold the rotors in proper position with the axes of the clamp-boxes in accurate alinement. The clamp-boxes, having been loosened, and the tool-holder withdrawn, and the gage-block placed on the wing of the tool-holder, the crank-shaft is turned until the completed crank-pin 24 rests upon the gage-block, whereupon the clamp-boxes are tightened 95 100 and the index-pins withdrawn, leaving crank-pin 26 in the line of collimation ready to be completely turned. This second crank-pin 26 having been completely turned, the rotors are again locked by the index-pins in 105 index-holes 17 and the second completely turned crank-pin 26 is brought down upon the gage-block as before which leaves rough crank-pin 25 in the line of collimation ready to be turned. 110

The diagrams of Figs. 11, 12 and 13, illustrate a triple throw crank with three crank-pins arranged in series at an angular distance of 90°. In these diagrams:—27, indicates the first crank-pin: 28, the second 115 crank-pin: and 29, the third crank-pin. Assuming, in Fig. 11, that crank-pin 27 has been completely turned. The rotors being locked by the index-pins engaging detent holes 16, the crank-shaft is to be adjusted in 120 the clamp-boxes, as before explained, so that the completed crank pin 27 will rest upon the gage-block. This brings crank-pin 29 to the line of collimation, in which position it may be completely turned, after which 125 the crank-shaft may be re-adjusted to bring crank-pin 29 to the gage-block, bringing rough pin 28 to the line of collimation.

While I have illustrated the rotors as being provided with four index holes, it will 130

be obvious that in some cases a lesser number of index holes will answer the purpose and that the number provided will take care of about all of the angles ordinarily involved in multiple cranks and that in extraordinary cases a greater number of index holes may be provided in the rotors. It is my preference that the index-pins and the index holes be arranged radially to the axis 10 of the rotors but it is obvious that such radial arrangement is not essential.

I claim:—

1. In a crank-turning attachment of the character described, a pair of bearings, 15 rotors mounted therein and provided with means for carrying a crank-shaft with the axis of one of its crank-pins in line with the common axis of the bearings and provided each with a series of corresponding indexing apertures, an indexing-pin carried by each bearing and adapted to coöperate with said apertures, and means for locking said index-pins out of engagement with the apertures, combined substantially as set forth.

2. In a crank-turning attachment of the character described, a pair of bearings, rotors mounted therein and provided with means for carrying a crank-shaft with the axis of one of its crank-pins in line with the 20 common axis of the bearings and provided each with a series of corresponding radial indexing apertures, a radial indexing-pin carried by each bearing and adapted to coöperate with said apertures, and means for locking said index-pins out of engagement with the apertures, combined substantially as set forth.

3. In a crank-turning attachment of the character described, a pair of bearings, rotors mounted therein and provided with means for carrying a crank-shaft with the axis of one of its crank-pins in line with the common axis of the bearings and provided each with a series of corresponding indexing 40 apertures, an indexing-pin carried by each bearing and adapted to coöperate with said apertures, racks formed upon the indexing-pins, pinions mounted in the bearings and engaging the racks, cranks connected with said pinions, and detent devices connected with said cranks to serve in locking the indexing-pins out of engagement with the indexing-apertures, combined substantially as set forth.

4. In a crank-turning attachment of the character described, a pair of bearings, rotors mounted therein and provided with means for carrying a crank-shaft with the axis of one of its crank-pins in line with the

common axis of the bearings and provided 60 each with a series of corresponding indexing-apertures, an indexing-pin carried by each bearing and adapted to coöperate with said apertures, racks formed upon the indexing-pins, pinions mounted in the bearings 65 and engaging the racks, cranks connected with said pinions, detent devices connected with said cranks to serve in locking the indexing-pins out of engagement with the indexing apertures, and a spring coöoperating 70 with each detent-pin and tending to urge the pins into indexing apertures when the pins are not locked out of engagement with the apertures, combined substantially as set forth: 75

5. In a crank-turning attachment of the character described, a pair of bearings, rotors mounted therein and provided with means for carrying a crank-shaft with the axis of one of its crank-pins in line with the 80 common axis of the bearings and provided each with a series of corresponding indexing apertures, an indexing-pin carried by each bearing and adapted to coöperate with said apertures, means for locking said index-pins 85 out of engagement with the apertures, and a gage-block adapted to be supported from the lathe-bed temporarily below a completely turned crank-pin to serve in positioning another crank-pin in the line of the axis of 90 the bearings, combined substantially as set forth.

6. In a crank-turning attachment of the character described, a pair of bearings, rotors mounted therein and provided with 95 means for carrying a crank-shaft with the axis of one of its crank-pins in line with the common axis of the bearings and provided each with a series of corresponding indexing apertures, an indexing-pin carried by each 100 bearing and adapted to coöperate with said apertures, means for locking said index-pins out of engagement with the apertures, a gage-block adapted to be supported from the lathe-bed temporarily below a completely 105 turned crank-pin to serve in positioning another crank-pin in the line of the axis of the bearings, and a tool-rest provided with a wing adapted to enter between the cheeks of a crank and to give support to a tool working on a crank-pin disposed in the line of 110 the axis of the bearings and to support said gage-block, combined substantially as set forth.

AUGUSTUS M. SOSA.
